UNITED STATES PATENT OFFICE.

STERLING ELLIOTT, OF NEWTON, MASSACHUSETTS.

CONTROLLING MEANS FOR CENTRIFUGAL OIL-BURNERS.

1,371,231.

Specification of Letters Patent. Patented Mar. 15, 1921.

Application filed April 27, 1918. Serial No. 231,287.

To all whom it may concern:

Be it known that I, STERLING ELLIOTT, a citizen of the United States, residing at Newton, in the county of Middlesex and State of Massachusetts, have invented an Improvement in Controlling Means for Centrifugal Oil-Burners, of which the following is a specification.

This invention relates to improvements in controlling-means for oil-burners.

In such types, there is provided a casing, in general, in the form of a furnace body, wherein there is mounted a distributor, through which the fuel, from any suitable source of supply, is delivered in the form of spray, jets or streams over a comparatively large area on a burner plate, through the centrifugal force of same incident to the rotation of the distributor by a motor. The liquid fuel within the furnace or casing is ignited by a pilot-light arranged for continuous burning to guard against the probability of extinguishment of the flame in the furnace through the temporary cessation of the flow of fuel from any cause.

As ordinarily arranged, the motor for the operation of the distributor is of the electric type for convenient power transmission and control, and it is with particular regard to such a type of motor operator, that the present invention is concerned. In the use of furnaces of this type, it sometimes happens that the pilot-light is extinguished through failure of the gas supply thereto, or for any other reason, and under such circumstances, unless the motor is controlled, the distributor continues in operation with a consequent flooding of the oil or other fuel with entailed loss.

One of the objects of the invention, therefore, is to provide a co-operating structure, preferably mechanical, that, if, for any reason, the oil, when delivered from the distributor, is unconsumed, and such unconsumed fuel, upon suitable accumulation thereof, will automatically operate to break the circuit of the motor with the effect to stop the distributor and prevent further delivery of oil to the furnace.

Furthermore, in direct connection with the pilot-light for such furnaces, and the liability of same to become extinguished, a further object of the invention consists in arranging the pilot-light, so that its ignition points are wholly below the bottom plate, but are yet arranged with a view to

directing flame from such point, to a point above the bottom plate, so that it may be readily reached by the fuel.

The invention further contemplates the provision of a control of the motor-circuit through a remotely located thermostat to provide for automatically governing the burning of the fuel in accordance with desired heat conditions, the thermostat proper being, of course, adjustable to vary the degree of heat at which it will automatically open or close the motor circuit. As the thermostatic control would close the motor circuit to start the motor feeding device at a certain minimum degree of heat, if, at such time, the pilot-light is out, a starting of the feeding device would result in accumulating oil in the furnace which would reach and operate the mechanical control for the motor circuit. The mechanical control will thus act to guard against operation of the feeding device to waste the oil under the starting of the thermostatic control, unless proper conditions exist for the burning of the oil.

The present invention, therefore, is directed to independent control means for the actuating motor of the furnace fuel-distributor, one of such control means being mechanical, and governed by the weight of the liquid fuel in the event such fuel in predetermined quantity should reach the control for any reason, as, by the failure of the pilot-light, and a second automatic thermostatically-governed control in which the motor circuit is opened or closed in accordance with predetermined heat conditions at a point or points beyond the furnace.

A fuel regulating valve is customarily connected in the fuel line between the fuel pump and the fuel distributor to govern the amount of fuel fed to the furnace and consequently the degree of heat of the furnace. In the normal operation of the furnace the fuel valve is adjusted to admit the passage of the required and relatively small amount of fuel. When however, it is desired to set the furnace in operation, the adjustment of the fuel valve for the operative condition of the furnace is such as to admit insufficient oil to readily start combustion, it is consequently necessary to open the fuel valve beyond its normal condition, to admit sufficient additional fuel to the furnace to permit ignition. After combustion has once started, the fuel valve may be adjusted to

its former condition to permit the normal fuel flow to the furnace. Because of the small amount of oil necessary to support combustion after it has once started, the adjustment of the valve to its original position is a difficult matter.

A further object of the invention is in the provision of means associated with the fuel regulating valve whereby the valve may be opened a predetermined amount to permit the additional flow of fuel necessary to enable combustion to be started and after which the valve may be easily and accurately returned to its initial setting.

15 The means comprises a pivoted lever to which the fuel valve stem is connected, which lever is movable between two adjustable stops, one of which corresponds to the normal setting of the valve and the other to the starting position of the valve. A movement of the lever to a position against one or the other of the stops accurately determines the setting of the fuel valve.

Another object of the invention is in the provision of means whereby the setting of the fuel valve is automatically adjusted by the operative or inoperative condition of the furnace, whereby, with the furnace in operation the fuel valve will be set for the normal fuel flow and with the furnace not in operation and the fire out, the valve will be set for the starting fuel flow.

The means whereby this object of the invention is accomplished is in the provision of a thermostat arranged in the path of the exhaust furnace gases to be heated by them, and having operative connection with the fuel valve. With the furnace in the inoperative condition with the fire out, the thermostat is contracted and thereby has moved the fuel valve to a position corresponding to the starting fuel flow, thereby admitting a large volume of fuel to the fuel distributor to facilitate the ignition of the fuel. 45 After combustion has been started, the hot exhaust gases operate to expand the thermostat to adjust the fuel valve for the normal fuel flow.

In the drawings:—

50 Figure 1 is a view illustrating the application of the invention to a furnace of the particular type.

Fig. 2 is an enlarged view of the switch through which the motor circuit is thermostatically controlled.

Fig. 3 is an end view of the same.

Fig. 4 is a detail illustrating particularly the mechanical control of the motor circuit in the event of leakage of unconsumed fuel.

60 Fig. 5 is an enlarged sectional view illustrating the pilot-light.

Fig. 6 is a plan view of the same.

The present invention, as illustrated, is applied to a particular type of furnace of a well-known construction, which, for the sake

of the present description, may be briefly referred to as comprising a furnace 1, of any appropriate type, having arranged therein a slightly concave burner-plate 2, suitably supported at an appropriate height in the furnace, with the support centrally formed and having a conical casing 3, to receive a conical head 4 of the distributor, which head, immediately above the plane of the burner-plate 2, is formed with a series of 75 apertures or ducts 5, disposed in an annular row with a series of directing fingers 6, projecting beyond the mouths of the ducts. The head 4, which is of hollow type, is carried by and communicates with the pipe-section 80 7, which is suitably supported at the lower end in a well 8, to which fuel, such as oil and the like, is delivered to a pipe 9, by a pump 10, suitably supplied from any appropriate source. The connection between pipe 85 7 and well 8 is such to insure against leakage, and the pump and also the distributor are operated from a motor 11, shown as an electric motor. The connection between the power-shaft 12, operated by the motor, and 90 the pumping distributor may be of any desired type, so long as the pump is operated to deliver the oil under pressure, and the distributor rotated with sufficient speed to distribute the oil through the ducts 5, with 95 a centrifugal force over the face of the burner-plate 2.

A device of this character requires the use of a pilot-light to initially ignite fuel, and it is important that such pilot-light 100 be arranged beyond the probability of becoming extinguished. The pilot-light for use with the furnace of the type described is illustrated more particularly in Fig. 5, and comprises a tubular section 13, fitted at 105 the lower end, at 14, for connection with a supply-pipe and formed above the lower end with an annular enlargement 15, the lower edge of which is sharply inclined outwardly and inwardly to form a bearing surface 110 16. The section 13 is formed at its upper end with a deflecting-plate 17, preferably slightly convex on the upper surface with the lower surface beyond the section, presenting a compound curve, as at 18, the 115 terminal phase of the curve, next the free edge of the deflector, being downwardly. The section 13 of the pilot-light is formed in a longitudinal bore 19 for the passage of the fuel, and in the annular enlargement 15 120 thereof there is formed a plurality of comparatively minute passages 20, communicating at their inner ends with the bore 19, and inclining upwardly therefrom and opening through the upper surface of the enlargement 125 immediately adjacent the body of the section. The upper terminals of the passages 20 form the ignition points of the pilot-burner, and, as will be clear from Fig. 5, such ignition points are arranged well 130

beneath the deflector plate, and the line of inclination of such passages being approximately on a line with the extreme edge of the deflector plate.

- 5. To dispose the pilot-light beyond the reach of the fuel delivered from the distributor, and also to protect such light against possibility of being reached by the fuel at the ignition point, and also to protect it
- 10 against other causes tending to extinguish it, there is arranged in the burner plate 2, a well 21, preferably removable, having a pedestal 22 rising interiorly thereof from the bottom, and formed at its upper end to
- 15 provide a seat for the bearing surface 16 for the pilot-burner. The pedestal has a longitudinal opening to permit the passage of the body of the burner below the enlargement thereto. The pilot-burner is thus centrally supported within the well, and the well is proportioned with more or less regard to the proportions of the burner for particular purposes. For example, the diameter of the well is slightly greater than
- 20 25 the diameter of the deflector of the burner to thereby provide an annular passage 23 about the burner through which the flame passes to reach the oil on the burner-plate.

Furthermore, the relative depth of the well, as compared with the height of the burner, is such that the upper portion of the deflector plate is approximately in line with the top of the well, that is, with the surface of the burner plate, so that the ignition points of the pilot-light are wholly below the burner plate, and protected against drowning from the fuel, as such fuel cannot directly reach the ignition points of the pilot burner without filling the well, and this possibility is guarded against through the provision of outlets 24, formed in the bottom of the well, which outlets, in addition to taking care of the oil leakage, provide a suitable air supply to the pilot-light.

45 In the event of failure of the pilot-light, it is apparent that with the distributor still operating, the fuel would accumulate and flood the furnace. As stated, one of the objects of the invention is to provide means whereby, in the event of failure of the pilot-light, the fuel supply will be practically cut off. This control is obtained by utilizing the weight of the unconsumed oil for operating a mechanical trip to open the switch

50 55 for the motor-circuit. In the preferred details here shown, such mechanical control comprises an electric switch including spaced terminals 25, 26, included in and forming part of one of the conductors 27, of the motor-circuit, and a co-operating bridging-block 29, said block being carried upon one end-portion of an L-shaped lever 30, pivotally mounted upon an appropriate part, and connected to a spring 31, tensioned to so move the lever as to withdraw

the block from the terminals. A second L-shaped lever 32 is pivotally supported in appropriate relative position to the level 30, the end of one arm of said lever 32 being formed to underlie the end of the appropriate arm of the lever 30, when said lever is in circuit-closing position, and the relative arrangement and size of the respective levers is such that when the lever 32 is in normal position, that is, against a stop 33, being there held by the counterweight 34, carried on the extension of the lever 32, the lever 30 will be held in switch-closing position against the influence of the spring 31.

That end of the lever 32, remote from the lever 30, is provided with a receptacle 35, to which the fuel may be delivered from a pan 36, supported in the furnace casing below the well 21, and in position to receive oil passing through the openings 24. The pan 36 is or may be removably supported and is preferably formed with a downwardly-inclined bottom 37, and for convenience has a pipe delivery 38 extending over the receptacle 35.

It is apparent, that, in the event of failure of the pilot-light, or for any other cause, the distributor will cause the accumulation of oil or other liquid fuel in the pan 37, through which it is delivered to the receptacle 35, and if, or when any predetermined weight of such fuel, adjustably governed by the weight 34 of the lever 32, accumulates in the receptacle 35, the lever 32 will be moved from the stop 33, thereby releasing the switch-lever 30, and will permit the spring 31 to operate the lever 30 to open the switch, and stop the motor 11. Consequently, the further delivery of oil is stopped, and waste, otherwise incident to the lack of said control, avoided.

In the mechanical control described, the additional pan 36 is of importance, and it is furthermore of importance that the receptacle 35 be covered, except in so far as may be necessary to permit the delivery thereto of the oil. These described characteristics are essential to the practical operation of the device, as naturally there would be an accumulation of dirt, dust, and the like in the pan from the furnace, and if such pan were utilized as the overbalancing medium for the lever, it is apparent that the accumulation of such dirt, or other refuse, would tend to operate the pan and cut off the supply of oil without the necessity for such action. Therefore, the pan 36 is usually not movable as a part of the controlling-means and any accumulation of dirt or other refuse therein will not affect the operation of the device, that is, the oil delivered to the pan simply finding its way through such refuse and through the discharge opening into the receptacle. The receptacle is guarded against being operated by the weight of ac-

cumulated refuse by covering such receptacle against the admittance of such refuse.

In addition to the mechanical control for the provision of waste of the fuel, the invention contemplates a thermostatic control to be governed by particular heat requirements. This control involves an appropriately-located motor-driven switch electrically controlled by a thermostat. The motor-controlling switch involves a suitable train indicated generally at 38, which is preferably spring-driven. One shaft of the train, as 39, provided with a switch-arm 40, carrying a contactor 41 adapted in one position of the arm to bridge the spaced terminals 42, included in the motor-circuit, the particular arrangement of the contactor and terminals being of no particular importance, although it is preferred that the terminals be in the form of the spaced plates, divergent in opposition to the rotation of the arm 40, so that the contactor 41 may readily pass between the contacts and effectively bridge the same electrically closing the circuit.

Movement of the train is thermostatically controlled for which purpose the arbor shaft, as 39, bearing the arm 40, is provided with a control disk 44, having diametrically opposed notches 45, to receive the nose 46 of a pivotally-supported L-shaped lever 47. One arm of the lever forms the armature 48 of an electro-magnet 49. The electro-magnet 49 is arranged in a circuit including a source of energy 50, having a conductor serially including a thermostatic element 51, the electro-magnet and the arbor shaft 39 of the train.

A thermostatic element coöperates with contacts 52, 53, here shown as screws, threaded for adjustment in suitable supports, so that they may be adjusted to vary the closing limit of the thermostatic element, to thereby vary the degree of heat through which the device operates. Each contact is, of course, in an independent circuit, the conductor 54 being common to both circuits. For example, the contact 52 is in circuit with conductor 55, leading to contact 58, adjacent the train and contact 53, 50 has a conductor 57 leading to a similar contact 56, diametrically opposed with relation to the contact 58. On the arbor 39 is fixed an arm 59, adapted to be moved in any particular switch-operating movement of the train, being so arranged that in one or the other locking position of the train, that is, with the nose 46 of the lever 47 in a notch 45, the arm 59 will engage one of the contacts 56 or 58, and so complete one 60 of the local-circuits at this end. A lever 47 is influenced in the direction from the electro-magnet by a spring 60, and such lever is utilized as a means for providing a lock to stop the train in predetermined positions, 65 whereby entire dependence for such lock

upon the engagement of the lever nose with the notches of the disk is not relied upon.

The lock contemplated comprises a spring-plate 61, secured to the armature and having a free end, and an arm 62 arranged on an escapement or other appropriate gear of the train adapted to engage the free end of said armature.

In the thermostatic control, the engagement of the thermostatic element with either 75 contact 52 or 53, will, in the event the arm 50 engages a corresponding terminal, energize the electro-magnet, attract the armature, release the lock and free the nose 46 from the particular notch in the disk. Under the influence of the spring-motor, the train, revolves a half revolution, the immediate effect of the initial movement separating the arm 59, from the particular contact, as 56, and breaking the local-circuit. 80 The main-motor-circuit is, in the instance illustrated, immediately broken and the motor stops, cutting off fuel supply to the furnace and thereby eventually lowering the heat in degree. The train continues movement until the lock 61, 62, is brought into effective use. In such locked position, the nose 46 of the lever is engaged in the diametrically-opposed notch, and the arm 59 engages the other contact, as 58, so that in 85 the reverse movement of the thermostatic element, the reverse action occurs and the motor-circuit is again closed and the motor started.

The means whereby the amount of oil fed 100 into the fuel distributor may be increased over the normal fuel flow to facilitate the initial ignition of the fuel and subsequently accurately decreased to the normal fuel flow includes a valve 65 in the fuel pipe 105 9 extending from the pump 10 to the fuel distributor. The stem 66 of the valve is slidably arranged therein and its upper end is pivoted to a lever 67 pivoted at 68 to a support, not shown. Said lever is movably 110 arranged between two adjustable stops 69 and 70 which serve to limit the motion of the lever in either direction, and by so restricting the movement of the lever, operate to restrict the movement of the valve stem 115 between a maximum and a minimum opening which can be varied by changing the adjustment of the stops.

A spring 71, attached to the end of lever 67 tends to normally maintain said lever 120 against the lower stop 70 and so maintains the fuel valve 65 in adjustment for the normal and minimum fuel flow to the distributor.

It is apparent that in starting the furnace, the lever 67 may be moved upward against the stop 69 to consequently open the fuel valve to permit the starting fuel flow and once the combustion of the oil in the furnace has begun, the lever may be 130

5 moved against the lower stop 70 and thereby adjust the valve for the minimum and normal fuel flow. By the provision of the stops 69 and 70, the valve may be moved 10 to the starting position and thereafter returned to the running position after each 15 operation with ease and certainty.

The thermostatic control of the fuel valve, whereby said valve is automatically opened 10 to the starting fuel flow position when oil is not burning in the furnace, and closed to the normal fuel flow position after combustion has begun includes the rod 72 preferably of a high temperature coefficient of 15 expansion, placed in the path of the hot exhaust furnace gases, and as shown, is placed in the flue 73 connecting the furnace with the chimney 74 and one end of the rod is fixed against movement in a bracket 75 20 secured to the chimney. The other end of the rod projects through the flue and is slidably arranged in and supported by the bracket 76 secured to the flue. The protruding end of the expansible rod has adjustably arranged thereon a member 77 25 formed with two extensions 78 in one of which a screw 79 is movably arranged. One arm 80 of a bell crank lever is disposed between an extension 78 and the screw 79 and 30 the movement of the rod 72 by expansion or contraction thereby causes a consequent movement of said arm. The other arm 81 of the bell crank lever is connected by a rod 82 to the end of the lever 67 governing the 35 fuel valve; whereby a movement of the expansible rod 72 caused by a variation of temperature of the flue gases may cause a corresponding adjustment of the fuel valve.

The bell crank lever is pivoted at 83 to a 40 support 84 securely maintained against movement in order that the total expansion of the rod 72 may be utilized.

When no oil is burning in the furnace and the temperature of the gas in the flue 45 is relatively cold, the rod 72 is at a minimum length and will have moved the bell crank lever to raise lever 67 against the action of the spring 71 to a position against the upper stop 67 thereby adjusting the fuel 50 valve 65 for the starting fuel flow. When

combustion has once started in the furnace and the flue gases have become relatively hot, the rod 72 expands and consequently operates to move lever 67 to a position against the lower stop 70 to thereby adjust 55 the fuel valve for the normal fuel flow, in which position it is maintained during the operation of the furnace.

Any expansion or contraction of the expansible rod 72 beyond that equivalent to a 60 movement of the lever 67 between the adjustable stops 69 and 70 is compensated for in the elasticity of the connections between the rod and the lever 67.

I claim:—

1. An oil-burning furnace having a fuel feeding-device operated by an electric-motor, a pilot-light for the fuel, a thermostatic control for opening the circuit of the motor at a predetermined maximum heat degree 70 from the burning fuel and closing the circuit at a predetermined minimum heat degree, and means operated by a predetermined weight of unconsumed fuel delivered from the furnace beyond the feeding-device 75 to open the motor-circuit independently of the thermostatic control, whereby to stop the motor when started by the thermostatic control on failure of the pilot-light.

2. The combination of an oil burner, 80 means for feeding oil to said burner including a fuel pipe, a fuel regulating valve in said pipe movable to a position corresponding to a starting fuel flow and to a running fuel flow, and thermostatic means 85 governing said valve arranged to adjust said valve into a position corresponding to the starting fuel flow when the oil fed to the furnace is not burning, and to move said valve to a position corresponding to the 90 running fuel flow subsequent the ignition of the oil in the furnace.

In testimony whereof, I have signed my name to this specification, in the presence of two subscribing witnesses.

STERLING ELLIOTT.
